JASPER N. HOWARD, OF WICHITA, KANSAS.

TYPE-WRITING MACHINE.

SPECIFICATION forming part of Letters Patent No. 513,110, dated January 23, 1894.

Application filed September 21, 1892. Serial No. 446,501. (No model.)

To all whom it may concern:

Be it known that I, JASPER N. HOWARD, a citizen of the United States of America, residing at Wichita, in the county of Sedgwick and 5 State of Kansas, have invented certain new and useful Improvements in Type-Writing Machines, of which the following is a specification, reference being had therein to the accompanying drawings and the letters and figures of reference thereon, forming a part of this specification, in which—

Figure 1, is a top plan view of the machine, having portions broken away to more clearly show the construction; Fig. 2, a sectional elevation on line X, X, of Fig. 1; Fig. 3, a similar view on lines X', X', of Fig. 1; Fig. 4, a bottom plan of the paper holding carriage of the machine; Fig. 5, a sectional elevation on line X'', X'' of Fig. 1, and Figs. 6, 7, 8, 9, 10, 20 11 and 12 are detailed views of portions of the machine.

This invention relates to certain improvements in that class of type writing machines wherein a single index key is used, adapted 25 to be turned on a pivoted center, and by connected mechanism, bring the type into operative position, and consists in the particular construction and arrangement of parts, which improvements are fully set forth in the following specification and pointed out in the 30 claims.

Referring to the drawings, a frame A, which is preferably of cast metal, is made of such form as to support the operative parts of the 35 machine, and in its construction is made with transverse guide ways G, G, at one end upon which the paper holding carriage C of the machine is arranged to slide. Said carriage consists of a frame; one part comprising the 40 end pieces S, S, and the longitudinal connecting bars O and 2 and ratchet bar R'', the bars 2 and R'' being arranged, resting and sliding on the ways G, G, of the frame; and the other part comprising the end pieces S', 45 S', hinged at their rear portion on bar O, and of the longitudinal connecting parts S'' and y, which frame supports the paper holding and feeding rolls R and R', as shown.

A rock shaft L is journaled at each end in 50 the end pieces S of the carriage frame, and bears at either end a side extending arm 21

each of said arms resting under a portion 25, of the roll holding frame, in such manner that, when the shaft is rocked said arms will be operated to raise said platforms, upward, 55 and thereby cause the said roll holding frame to turn on its hinged bearings and elevate the rolls R, R'; said shaft L being provided with a centrally depending arm 20 which is engaged and operated to thus operate the 60 shaft and its arm 21. A rock frame, comprising a horizontal bar m and trunnions m' is journaled, by means of said trunnions, in corresponding bearings in the frame A in such manner as to be parallel with the movement of carriage C, and so the bar m will rest adjacent arm 20 of rock shaft L. Said frame is further provided with a depending arm M'' connected with a bell crank lever 9, which is fulcrumed to a standard 10 which 70 is secured to the upper side of frame A, through the agency of a connecting rod 24; the said bell crank having one arm arranged extending down through an opening in frame A for the purpose of effecting such 75 connection, while the opposite arm of said lever terminates with a finger key, which is adapted to be pressed down to operate the lever, which movement causes the said rock frame to be operated, which in turn engages 80 arm 20 of rock shaft L, at any position of carriage C, and causes said shaft to be rocked, its arms 21 to be raised, and the hinged frame of the carriage to be actuated to elevate the paper holding rolls. If desired, said adjustment of 85 parts may be held by means of an extending arm e of a swiveled post 11 which is arranged adjacent the horizontal portion of lever 9, by turning said post to bring said arm e over the lever, as shown in Fig. 3, but when the lever 9 90 is not held by said arm e, a coil spring t, arranged on one trunnion of the rock frame m, m', and given tension by connecting one end with the frame A and one end with the said rock frame, will return said rock frame, connecting rod, and lever, to their normal position. 95

H represents a type bar head, and is made circular in form, and is provided about its periphery with a series of notches as shown at a in Figs. 10 and 11, and with an annular groove a' also shown in said figures, with an

annular flange H' on its upper side, and with a toothed gear wheel B on its under side, as shown.

2 represent the type bars, each bar being 5 made at its lower end to fit a notch a of head H, and each bar being further provided with a hole arranged to register with the base of the annular groove a', of head H, when the bars are arranged in their notches a, and when thus 10 arranged the said bars are jointly fulcrumed in their respective notches by means of a wire a'' (see Fig. 11), which is arranged in the annular groove a', and passed through the holes of the type bars; the wire ends being suitably secured to hold the same thus arranged. The said type bars are further provided, individually, with an extending foot piece d, at their lower end, and with a capital letter and a small letter at respective points at their 15 upper portion, as shown in Fig. 9, (which represents the two characters of type of letter D—d,) and with a connected coil spring 3, which is connected with the annular flange H' of head H. The feet d of the type bars 20 serve as a part to be engaged by a downwardly moving device to operate them, and the coil springs 3 serve as a means of yieldingly holding them erect when not being operated. The said type bar head is arranged 25 30 in a horizontal position on the upper central portion of the frame A so as to bring the type bars adjacent the paper holding roll R, where it is pivotally secured by a stud N.

A toothed segment D is arranged on frame 35 A in mesh with wheel B of head H, and is pivotally secured, between a cross-plate F and the surface of frame A by means of a rod 6, which also serves as a connecting rod of a lever mechanism. Said segment is made with 40 an extending arm which terminates with a fork 5 wherein the machine index lever 4 is fulcrumed, as shown. At the under side of frame A is a lever 17 fulcrumed to a depending part 22, and connected at one end with 45 the index lever 4 through the agency of rod, 6, and at its opposite end with a lever 18 which lever is fulcrumed to frame A, as shown, and bears an upright arm 1 which terminates at its upper end with an over-reaching part, 50 extending toward the type bar head, and in such position as to be immediately over the foot d of the type bar 2 which is brought to rest at the printing point, and by such arrangement of levers, a down movement of the 55 free end of index lever 4 will cause a corresponding down movement of arm 1 of lever 18, causing the over-reaching part of said arm 1 to engage the foot d of the adjacent type bar, and thus operate said type bar so its type 60 end will move toward and strike the paper holding roll R; the index lever 4 being adapted to be moved horizontally, at its free end, above an index plate, which is semicircular in form and bears the several letters of the alphabet, figures and other characters common 65 in type writers, and when moved, correspondingly operates the segment D which in turn

operates gear B and correspondingly turns the head H, and the type bars are so arranged that when lever 4 is brought above a certain 70 letter or character, of the index, the corresponding type bar will be brought so its foot d will be under the over-reaching part of arm 1 of lever 18, so that a down movement, at such position, of lever 4, will cause said 75 type bar to be operated, as described, for the purpose of causing the lever 4 to be exactly in line with the letter or character of the index. When brought down, it is made, at its under side adjacent the finger piece, wedge 80 shaped, and about the index is arranged a notched rack 7, which is secured to frame A, and provided with a V-shaped notch in line with each letter or character, and when the lever 4 engages said rack, its wedge shaped 85 part registers in a V-shaped notch, thus centering, or lining the lever, (see Fig. 6,) which insures the correct position of the type bars 2, as they are brought about to be operated. Fulcrumed to frame A, adjacent arm 1 of 90 lever 18, and arranged to operate transversely to said lever 18, is a lever 16 carrying on the upright portion a spring pawl P arranged to engage the teeth of the ratchet bar R'' of the paper holding carriage C, the spring thereof 95 being shown at P'; a horizontally extending arm 23 of said lever 16, is arranged under a side extending lug 19 of arm 1, and the upright portion of said lever is connected, through the agency of a wire g with a coil 100 spring in barrel 15, which spring yieldingly holds said lever inclined in one direction, holds arm 23 thereof against lug 19 of arm 1 with sufficient tension to support said arm 1 and hold the lever 18 and the levers connected 105 therewith in their normal position. By such construction and arrangement of parts, last described, at each down movement of index lever 4 a type bar 2 is operated to cause its type to strike roll R of the carriage C, and simultaneous with such movement the lever 16 is thrown to shift the pawl P backward a distance sufficient to engage the next succeeding tooth of ratchet bar R'' of carriage C, by reason of lug 19 of arm 1 carrying down, 110 therewith, on the arm 23 of lever 16, and as the index lever 4 is released the spring in barrel 15 will, by reason of its tension, reverse 115 said movement and thereby release the operated type bar, and through the agency of 120 pawl P move the carriage C along on its way, one space, at each such movement.

As a means of raising pawl P so as not to engage the ratchet bar R'', at times when it is desired to independently shift carriage C 125 along on its ways, said pawl is provided with a side extending wing P'' (see Fig. 7) and a lever 12 is provided, fulcrumed on frame A as shown at 13, the said lever having a finger key, as shown, which is supported by a spring arm f as shown in Fig. 1, and the opposite end portion 14 of said lever is arranged resting under the wing P'' of said pawl, so that a down 130 movement of the finger key of said lever will

raise lever end 14 and cause it to engage the pawl wing and correspondingly raise the pawl.

5 E represents a hood placed over the type head H and type bars thereof, and serves as a protector for said parts, and is made open at the side adjacent carriage C in order that the type bars may strike the platen, and is cut away so as not to obscure the place where 10 the type bars engage roll R of the carriage.

I represent ink rolls, and in Fig. 12 they are represented arranged in a frame I'. Two sets of such ink rolls and frames, are used, one set being arranged within hood E at each side 15 of the side opening of the hood, being held, so the type of bars 2 will engage therewith, when head H is moved in either direction, and be inked ready to effect a print, when they are brought into proper position for operation. Such position of the inking rolls is shown in Figs. 1 and 2, and the hood E is made with an opening adjacent each outer roll of each set, so that they may be accessible 20 to be supplied with ink at times required.

25 Secured to an extending portion of one journal of roll R, of the carriage C, is a hand wheel J having on its inner side a ratchet wheel J', and fixed to frame end S' is a spring pawl J'' arranged engaging said ratchet wheel. Rotation of the roll R is accomplished by operating the hand wheel J, the pawl J'' preventing a wrong direction of movement, and the ratchet J' serving as a 30 gage, so that a like distance may be made at each movement.

35 The paper employed in writing is passed from the rear, between the rolls R, R' as shown in Fig. 2, and when being placed, the longitudinal curved, plate z, of the carriage, serves 40 as a means of directing the paper upward, and when beyond said plate it is placed under a series of clamping fingers v, which are attached to a rock shaft w, which is journaled, at its ends in bearings of upright portions of frame ends S', S', and is provided at 45 one end with a laterally extending arm w' held up into position by means of a spring, as shown at w'' in Fig. 8, which spring serves as a means, in thus holding arms w', to exert 50 a light tension to yieldingly hold down the series of fingers v on the paper, and when placing or removing the paper said arm w' may be pressed down, which will correspondingly raise arms v.

55 It has heretofore been stated that the type bars 2 are each provided with two type or characters, and it has been described in what manner the paper holding rolls are elevated at times. The purpose of thus elevating said 60 rolls at times, is to bring the type engaging side of roll R into position so the type at the extreme end of the bars 2 will at such times effect a print, while the other type of the bar will be too low to effect a print. While in 65 the normal position of the roll R the lower type will effect a print and the upper type will be too high to effect a print, and as the

lower type are preferably of "lower case" letters, in the use of the machine it becomes necessary when it is desired to print a capital, to press down on the key of lever 9 until such print is made and then release said key, and if it is desired to print all capitals said key is held down by arm e of post 11 as described.

70 In the arrangement of the index of letters and characters of the machine, one space is left blank, as shown in Fig. 1, and the type bar corresponding with such space is either blank or omitted, and when the index lever 4 is pressed down at that place no print will be made, but the spacing pawl will be actuated to shift the carriage C the same, as when a print is made, which movement serves as a spacer, between words, at end of sentences, 85 &c., when spacing is required.

80 Having thus described my invention, what I claim as new and useful, and desire to secure by Letters Patent, is as follows:

1. The combination with the frame A and 90 paper holding carriage C, of the type-bar head H provided with the gear wheel, and with the series of type bars 2 disposed about its periphery, the springs for yieldingly holding said type bars; the segment D and index lever; and of the mechanism arranged to be actuated by said index lever, for operating the type bars and shifting the paper holding carriage, substantially as and for the purpose set forth.

95 2. In the type writing machine described, the combination with the carriage C, of the lever 16, the pawl thereof; the spring for operating said lever in one direction; the levers 4, 17 and 18 the connecting rod 6, and the arm 1 provided with the lug 19, substantially as, 100 and for the purpose set forth.

105 3. In the type writing machine described the combination with the paper holding carriage, comprising the compound frame for supporting the paper-holding rolls, of the rock shaft L provided with arms 21 adapted to engage and elevate the frame carrying the paper holding rolls, and with the depending arm 20; the rock frame journaled in the machine frame, and adapted to be operated to operate said depending arm; the bell-crank lever 9 having a finger key, and connected with said rock frame, through the agency of a connecting rod, substantially as and for the purpose set forth.

110 4. In the type writing machine described the combination with the lever mechanism, of the segment D the head H provided with the gear arranged in mesh with said segment, 115 the type bars disposed about the periphery of said head; the inking rolls arranged to be engaged by the type of said bars, and means for operating said type bars, substantially as set forth.

120 5. In the type writing machine described, the combination with the revoluble head H, of the type bars D jointed at their lower end portion to said head, and provided with the

laterally extending feet *d* adapted to be engaged and operated, to operate the type-bars, by the vertically actuated arm 1, of the arm 1 provided with the laterally extending portion at its upper end, of the springs for holding said type bars erect, and of the gear and lever mechanism for rotating said head and

operating said arm and type bars, substantially as specified.

JASPER N. HOWARD.
